Inventor

RALPH REED.

By Faulkner & Faulkner

Attorney.

UNITED STATES PATENT OFFICE.

RALPH REED, OF CINCINNATI, OHIO.

AUTOMOBILE HOOD RETAINER.

Application filed November 3, 1922. Serial No. 598,898.

To all whom it may concern:

Be it known that I, RALPH REED, a citizen of the United States, residing at Cincinnati, in the county of Hamilton and State of Ohio, have invented certain new and useful Improvements in Automobile Hood Retainers, of which the following is a specification, reference being had therein to the accompanying drawing.

- 10 My invention relates to automotive equipment, and in particular to latches for the hoods of automobiles.
- It is the object of my invention to provide a hood latch that will prevent rattling, will 15 be self-compensating for the warping and twisting of the several parts of the body of the hood, and which will resist the usual movements of the hood during the operation of the vehicle.
- 20 It is my object to provide a yielding resistance to such movements, and to provide a ready means of unlatching the latch.

It is a still further object of my invention to provide a resilient means interposed 25 between the parts of the latch so that there shall be no metal to metal contact, and, therefore, no passage through the latch of the vibrations which usually set up various types of noises.

- 30 It is a further object of my invention to provide a resilient means so located that it may be readily renewed, and that any accumulation of foreign material or moisture in it will be readily carried away.
- 35 It is an additional object of my invention to provide means to prevent the noises being set up in the plunger of the latch and its housing.

It is my object to provide a broad and 40 convenient handle which can be easily grasped by the operator.

It is my object to provide a hood latch that will only need a slight movement in order to unlatch it.

- 45 It is a further object of my invention to provide a broad bearing surface of the latch to reduce the wear to a minimum.

It is still an additional object to provide a 50 combined movement when the latch is locked so that the pull on the hood is both downwardly and inwardly.

Referring to the drawings:

Fig. 1 is a side elevation partially in section of one form of my latch in locked position.

Fig. 2 is a plan view of Fig. 3 with the hood in section;

Fig. 3 is a side elevation of the latch showing a slightly modified form of hood carried handle bracket;

Fig. 4 is a section on the line 4—4 of Fig. 5;

Fig. 5 is a section enlarged of the upper end of the plunger and the reciprocating housing;

Fig. 6 is a side elevation partially in section of a modified form of my latch;

Fig. 7 is a plan view of Fig. 6;

Fig. 8 is a section of the modified form of the washer arrangement within the casing.

Referring to the drawings in detail:

1 is a hood upon which is mounted a bracket having horizontal arms 2 and the diagonal arms 3 terminating in a cup 4 which is disposed at an angle to the hood. 75

This cup has an aperture 5 at the bottom thereof communicating with its interior. In the interior of the cup there is located a resilient member preferably of rubber designated 6. This member has a semicircular cup shaped cut away portion 7 which communicates with the aperture 5 by the passage way 8.

In this cup shaped portion 7 fits the ball 9 which is mounted on the end of the handle 10. This handle is a single rod bent back upon itself with a space for the fingers of the operator to grasp it. The handle terminates in a cup shaped member 11 which is internally threaded as at 12. This cup shaped member is threaded upon the casing 13 which terminates as at 14 in a supporting shoulder surrounding the plunger or piston 15. Adjacent this piston is a steel washer 16 closing the opening between 14 and 15. In order to prevent squeaking due to the positioning of the parts a positioning washer of lead, designated 17, is mounted upon the steel washer 16 within the casing 13 and surrounding the piston 15. 100

It will be noted that the lead washer is in contact with the walls of the casing 13, but this is not the case of the steel washer 16. Thus the squeaks that should be set up as a result of the casing of the steel washer are 105 eliminated. A helical spring 18 has one end mounted upon the lead washer and the other end in engagement with a washer 19 which is carried on the upper end of the piston 15. The retaining nut 20 is mounted on the 110.

plunger or piston in order to retain the washer 19 in position and to resist the action of the spring 18. The lower ends of the plunger or piston 15 terminates in a ball 21 and is mounted in a socket formed in the socket members 22 and 23 and the aperture 24 in the frame member 25 of the automobile which is located along the bottom edge 26 of the hood. This arrangement permits the usual movement of the entire plunger in its casing to accommodate it to the movements of the vehicle and the strains and shocks imposed upon it.

As will be seen in Fig. 4 the upper lead washer 19 is cut away as at 27 to permit of the ready mounting of the washer upon the plunger 15.

It will be noted that the hood is thus pulled downwardly and laterally against the inner ledge of the body frame designated 28. The several parts are so arranged that they easily clear the apron of the fender and permit the ready access of the operator's hand to operate the several parts. In addition to this, a handle is so arranged that the hand of the operator will not be injured by any slipping of the parts.

In operation, a slight pull upwardly to one side serves to unseat the ball 9 from the resilient member 6 and then to swing it out of engagement with the bracket thus permitting the hood with its bracket to be easily lifted. This lifting of the hood is naturally accomplished by reason of the fact that the arms 2 of the bracket are spread far enough apart to permit of the insertion of the hand of the operator, thus securing a firm hold upon the handle attached to the hood.

Turning to Figures 6 and 7, there will be seen a modified form which consists of the other bracket having a long resilient member 29 which has in its upper surface a trough 30 cut away to receive the broad bearing member 31 of the handle 10. The handle 10 has a pair of arms 32 supporting either end of 31. The resilient member 29 is supported in a long trough 33 carried by the arms 2 of the bracket. This member 33 together with the arms 2 form the handle for lifting the hood. In some forms of cars with a very long hood it is preferable to have this broad bearing surface to prevent the rocking of the hood with respect to the body. This resilient member 29 is also provided with an aperture 34 communicating with the aperture 35 in the bottom of the trough 33 for the exit of any accumulation of moisture or foreign material.

Otherwise, the construction is the same as in the preceding figures. The same dual movement of a downward and lateral pressure is present and the same feature of providing a broad handle for unlocking the latch is present in this form as in the other form.

It is the object of my invention to prevent the transmission of any shocks of the body to the hood, to prevent wear, and to reduce the noises usually found in hood constructions. The rattling of latches is one of the most frequent causes of body noises on automotive equipment.

A modified form of my means of preventing squeaks and rattles is seen in Fig. 8.

In this form I provide the steel housing or casing 13 in which moves the plunger 15 surrounded by the spring 18.

The bottom of the casing has a washer preferably of copper or other non-ferrous metal designated 36. Above it is a washer 80 of felt designated 37 and on top of that a washer of copper or the like designated 38. I am thus able to provide a seal for grease and oil to be packed in the casing and also provide washers which, while they will fit 85 closely against the plunger 15 and the walls of the casing will not squeak. The springs 18 serve to hold the several parts to one another firmly.

It will be understood that the pivotal connection 39 to the frame 25 may be of any desired character. I comprehend within the pivotal or swivel connections equivalent forms of universal connections.

It will be understood that I do not desire 95 to be confined to the detail embodiment illustrated and described but comprehend within my invention suitable modifications.

Having thus fully described my invention, what I claim as new and desire to secure by Letters Patent, is:—

1. In combination, a hood bracket, a latch member in contact therewith, and resilient vibration absorbing means interposed between said latching member and said bracket.

2. In combination, a hood bracket, a latch member in contact therewith, a resilient means interposed between said latching member and said bracket, and adapted to 110 permit of the free passage therefrom through the bracket of any accumulation of moisture or foreign material.

3. In combination, a bracket mounted on a hood, a locking member resiliently mounted on the body, resilient means on said bracket interposed between said locking means and the bracket, said locking means being so arranged that it can be locked by being elevated and rotated.

4. In combination, a bracket mounted on a hood which is adapted to engage laterally and vertically the body of an automobile, a socket in said bracket, a resilient member in said socket, a locking member having a handle and adapted to engage with said resilient member, and means attached to one end of said handle for attaching said locking member to the body of the automobile, said handle being adapted to be 130

rotated upon its means of attachment to the body and elevated when the locking means is unlocked from the bracket.

5. In combination, a bracket adapted for attachment to a motor vehicle hood a socket carried by the bracket, a resilient member therein, a handle in contact therewith at one end and carrying a casing at the other end, a plunger working in said casing, a 10 resilient means interposed between the plunger and the casing, a swivel joint adapted to connect the plunger with a motor vehicle body whereby when the several parts are connected to one another the hood will be held 15 downwardly and laterally inwardly, and when it is desired to unlock the handle from the bracket it is elevated against the resistance of the yielding means.
6. In combination, a bracket adapted to 20 form a handle for lifting a hood of an automobile to which the bracket is attached, a diagonally disposed socket carried by said bracket, a locking member, a resilient member in said socket cut-away to receive the 25 end of said locking member, a handle on said locking member, a casing connected to one end of said handle, a plunger working in said casing, resilient means between said plunger and said casing, and a swivelled 30 attaching member carried by said plunger adapted for attachment to a part of the body of an automobile with which the hood is in contact, whereby the hood is held in position relatively to the automobile body.
- 35 7. In combination, a bracket adapted to form a handle for lifting a hood of an automobile to which the bracket is attached, a diagonally disposed socket carried by said bracket, a locking member, a resilient member located in said socket, cut-away to receive 40 said locking member and adapted to permit of the exit of any accumulation of moisture, a handle on said locking member, a casing connected to one end of said handle, 45 a plunger working in said casing, and a swivelled attaching element carried by said plunger and adapted for attachment to a part of the body of the automobile with which the hood is in contact.

8. In combination, a bracket adapted to 50 the hood of an automobile, a locking member in contact therewith consisting of a handle attached to a casing, a plunger in said casing, a resilient means between said casing and said plunger, a swivel connection with 55 the plunger on the body of said automobile upon which the hood is mounted, and washers of relatively soft material such as lead engaging with either end of the resilient means and with the walls of the casing 60 to prevent the contact of the plunger with the casing, whereby noises due to the friction thereof are prevented.

9. In combination, a bracket adapted to 65 the hood of an automobile, a locking member in contact therewith including a handle, a casing carried by said handle, a plunger in said casing, a resilient means between 70 said casing and said plunger, a swivel connection with the plunger on the body of said automobile upon which the hood is mounted, and washers of relatively soft material such as lead engaging with either 75 end of the resilient means and with the walls of the casing to prevent the contact of the plunger with the casing, whereby noises due to the friction thereof are prevented, and a resilient member interposed between said bracket and said locking member to dampen the vibrations passing 80 through the assembled parts.

10. In combination, a handle attached to the hood of an automobile consisting of a pair of spaced arms and a trough connecting the outer ends of said arms, a resilient 85 member located in said trough having an extended cutaway portion in its upper surface, a locking member, a handle on said locking member having one end located in said trough, a casing connected with the other 90 end of said handle, a swivel member mounted on the body of the automobile carrying said hood, said member being connected with the casing and being free to turn.

In testimony whereof, I affix my signature.

RALPH REED.
